[57] CLAIM

The ornamental design for a sight aiming instrument for weaponry, as shown and described.

DESCRIPTION

FIG. 1 is a left, rear perspective view of a sight aiming instrument for weaponry, embodying my new design; FIG. 2 is a left, front perspective view thereof.

FIG. 3 is a right side elevational view thereof, with the left side elevation being a mirror image thereof;

FIG. 4 is a rear elevational view thereof;

FIG. 5 is a front elevational view thereof;

FIG. 6 is a top plan view thereof; and

FIG. 7 is a bottom plan view thereof.
